UNITED STATES PATENT OFFICE.

GEORGE A. DEITZ, OF CHAMBERSBURG, PENNSYLVANIA.

SEAL-LOCK.

SPECIFICATION forming part of Letters Patent No. 363,371, dated May 24, 1887.

Application filed June 14, 1886. Serial No. 205,179. (No model.)

To all whom it may concern:

Be it known that I, GEORGE A. DEITZ, a citizen of the United States, residing at Chambersburg, in the county of Franklin, State 5 of Pennsylvania, have invented certain new and useful Improvements in Seal-Locks, of which the following is a specification, reference being had therein to the accompanying drawings, in which—

10 Figure 1 is a side elevation of a portion of a car and door provided with my improved lock. Fig. 2 is a vertical section taken on the line α of Fig. 1. Fig. 3 is a like section showing the lock open.

15 Like letters refer to like parts in all the figures of the drawings.

The object of my invention is to provide a receptacle for a manifest or bill of lading, and a seal which shall be punctured, ruptured, or 20 defaced in the act of unlocking a car-door, in order to provide unmistakable evidence of unauthorized tampering with the lock.

Other objects and advantages will appear in the following description, and the novel features of my invention will be particularly 25 pointed out in the claims.

A represents a portion of a car-door; and, B the door-post, or a portion of the frame-work of the car adjacent to the door.

30 C represents a casting secured upon or recessed in the edge of the door, and provided with a projecting lug, C', having in its upper face teeth C² C³, the front face of the former being slightly inclined and that of the latter 35 substantially vertical. The casting C is also provided with an aperture, C', for the wire of an ordinary lead seal.

Secured upon and set within a recess in the 40 post B is the lock-case D, the upper portion of which is provided with a receptacle, D', for a bill of lading or manifest, which receptacle is closed by a cover, D², adapted to slide in grooves or flanges D³, formed as a part of the receptacle. The cover D² and the end 45 wall of the receptacle are each provided with apertures D⁴ D⁵, respectively, for the wire of an ordinary lead seal. The rear wall of the receptacle D' is slotted, as at D⁶, and over said slots I secure, by cement or in any other suitable manner, a paper, glass, or other breakable seal, E.

The lock-case D is constructed to form a main receptacle, F, for the operative parts of the locking and seal-canceling mechanism. These comprise a pivoted or pendulous locking-bolt, 55 G, and a similarly constructed and operating stamp-canceler, H. The locking-bolt is provided near its front edge with a seal-wire aperture, G⁶, and at its lower edge with teeth G' G², adapted to fit the teeth C² C³ of the door-casting. It is also provided with a finger-hold, G³, to facilitate disengaging the bolt from the door-casting.

A rod or bolt, G⁴, serves as a pivotal bearing for the locking-bolt, said rod being supported in the walls of the case. The upper edge of the locking-bolt is provided with a curved recess, G⁵, in which the lower weighted end of the canceling-lever rests when the door is locked. The remaining outline of the upper edge of the bolt is such that when it is turned upwardly on its pivot the canceling-lever is oscillated on its pivot H', so as to throw its upper end, which is made in the form of two blades, H², into the slots D⁴, and through 70 any seal arranged thereover, and within the manifest-receptacle D', as clearly shown in Fig. 3, whereby said seal is mutilated or destroyed, and serves as evidence that the bolt of the lock has been separated from the door-casting.

The operation of my invention will be readily understood from the above description, and it will be noted that all of the operative parts are securely contained within the lock-case, as well as the fastening-bolts I for the same, the heads of which are covered, while the threaded ends are within the car, so that access to the operative parts or to the seal is impossible without leaving evidence thereof. 90

Of course it is understood that an ordinary lead seal, as J, will be employed to retain the locking-bolt in connection with the door-casting, and also the sliding cover over the manifest box or receptacle thereof.

Having described my invention and its operation, what I claim is—

1. In a car-door fastening, the combination, with the pendulous seal-canceling lever H, of the pivoted locking-bolt G, having the curved recess G⁵ in its upper edge, and having teeth G' G² in its lower edge, a car-door casting hav-

ing teeth conforming to the teeth of the locking-bolt, and a manifest and seal receptacle the rear wall of which is slotted, substantially as specified.

- 5 2. The combination of the lock-case D, formed with the manifest-receptacle D', slotted, as at D⁴, and provided with a cover, D², having a seal-wire aperture, the pendulous seal-canceler H, the locking-bolt constructed 10 substantially as described, and the car-door casting having the lug C', provided with the teeth C² C³, substantially as specified.
3. The combination, with the door A, the

door-casting C, having the aperture C⁴ and lug C', with teeth thereon, the post B, and casing 15 D, set therein, and provided with the receptacle D', projecting downwardly into the main receptacle of the casing, and slotted, as described, the pendulous seal-canceling lever H, having the blades H², and the locking-bolt 20 adapted to swing the lever in its unlocking movement, substantially as specified.

GEO. A. DEITZ.
